UNITED STATES PATENT OFFICE.

LOUIS STEINBERGER, OF NEW YORK, N. Y.

INSULATOR-PIN.

No. 805,167.

Specification of Letters Patent.

Patented Nov. 21, 1905.

Application filed January 3, 1905. Serial No. 239,355.

To all whom it may concern:

Be it known that I, LOUIS STEINBERGER, a citizen of the United States, and a resident of the city of New York, borough of Brooklyn, in the county of Kings and State of New York, have invented a new and Improved Insulator-Pin, of which the following is a full, clear, and exact description.

My invention relates to devices for the support and insulation of electrical conductors, and more especially to insulator-pins used in connection with currents of high voltage.

My more particular objects are to so improve the insulation as to lessen the tendency under wet-weather conditions of a high-voltage current to arc over the surface of an insulator or its support or partly over the surface of an insulator and partly through the air from the conductor to the ground or to the support for the insulator, if this support be grounded. I also seek to preserve the insulating device and its accompanying parts from deleterious action by the weather and to enable it to be used for supporting insulators or for supporting a conductor directly, if desired.

In addition to the objects above enumerated I strengthen the support for the cable or other conductor and increase the durability of the support, so that it may do its duty fairly well even when broken or otherwise badly damaged. I also shield certain metallic parts not directly used in supporting the cable, so as to prevent the possibility of an arc to any part of the supporting-pin or of its immediate connections.

Reference is to be had to the accompanying drawings, forming a part of this specification, in which similar characters of reference indicate corresponding parts in all the figures.

Figure 1 is a vertical section through an insulator-pin made in accordance with my invention. Fig. 2 is an inverted plan view of the body portion of the pin removed from the cross-arm. Fig. 3 is a vertical section through the cap 25, of insulating material; and Fig. 4 is a plan view of the cap removed from the cross-arm.

The cross-arm is shown at 5 and is provided with a bored aperture 6 of the usual form. A tubular core 7, of metal, is provided with indentations 8, constituting anchorages, the upper end 9 of this tubular member being closed, the other end 10 being threaded externally and constituting a shank. Encircling this core is a mass of insulating material, preferably

"electrose," made up of a cylindrical portion 11, frusto-conical portions 12, 13, 14, and 15, and a shank portion 16. The cylindrical portion 11 is provided with an annular step or shoulder 17, the frusto-conical portions 12 and 13 are provided with annular steps or shoulders 18 19, and the frusto-conical portions 14 15 are provided with annular recesses 20 21. The frusto-conical portion 15 is surmounted with a cylindrical stem 22, threaded externally at 23 and provided at its top with a slot 24. The thread 23 is for the purpose of engaging an insulator, preferably of the so-called "hood" type, and the slot 24 is for the purpose of engaging a conductor directly should it be deemed advisable to use the same in the absence of an insulator.

Below the cross-arm 5 is a cap 25, of insulating material, preferably electrose, engaging a washer 25^a, of soft rubber. This cap is provided with facets 26, whereby its periphery is rendered angular for the purpose of enabling it to be readily turned. Embedded within this cap is a metallic portion 27, provided with an annular flange 28 and with a sleeve portion 29, the latter having a threaded portion 30 for engaging the lower end or shank portion 10 of the tubular core 7. A revoluble nut 31, threaded internally, also engages this threaded shank, and an annular washer 32 is preferably employed in connection with the nut 31, but being removable is not essential. The tubular core 7 is united to the jacket of insulating material encircling it preferably by molding, the anchorages 8 effectively preventing movement between the parts.

The insulator-pin is assembled as follows: The body portion of the pin, provided with a threaded shank 10, is mounted in the position indicated in Fig. 1, the shank 16, of insulating material, projecting nearly but not quite through the aperture 6. The washer 32 is next slipped loosely over the shank 10, the nut 31 is tightened so as to bind the washer 32 rigidly against the under face of the cross-arm, and the shoulder 17, of insulating material, is thus drawn down tightly upon the upper surface of the cross-arm. The washer 25^a, of soft rubber, and the cap 25 are next applied, the threaded sleeve 29 engaging the threaded shank 10. The purpose of this cap is not merely to reinforce the nut 31, though it incidentally has such a slight effect, but is mainly to insulate the nut 31, the shank 10, and all other metallic parts. Arcing is thus effectively prevented. The cap 25 and the washer

25^a being removable may be omitted, if desired. The shape of the anchorages 8 is immaterial, round shallow holes answering every purpose.

5 By the construction above described no metallic parts whatever are exposed either to the danger of arcing or to the action of the weather—that is to say, the tubular metallic supporting-stem 7 and all metallic parts in 10 electrical communication therewith are completely inclosed with insulating material. The washer 25^a serves as a gasket and excludes the entrance of moisture in case the under face of the cross-arm is wet.

15 The structure admits of general use, but is of special value upon lines in which a breakdown of the wiring might be disastrous to life and property.

I do not limit myself to the exact details of 20 any or all of the parts above described, nor to any particular combination of elements entering into the construction of the insulating pin. Neither do I limit myself to a hollow metallic core, nor to any particular material to 25 be employed in making any of the insulated parts.

Having thus described my invention, I claim as new and desire to secure by Letters Patent—

1. An insulator-pin, comprising a member 30 of insulating material provided with a slot for supporting a conductor, and also provided with a thread for supporting an insulator on said member of insulating material, and means for supporting said member of insulating material.

2. As an article of manufacture, a metallic member provided with a shank portion, and insulating material enveloping said metallic member but leaving said shank portion exposed, said insulating material having a threaded portion and also a slot for engaging a conductor.

3. An insulator-pin, comprising a body portion of insulating material, a metallic core 45 partially embedded within said body portion, and having one of its ends extending beyond the bounds thereof, said body portion being provided with means for engaging an insulator, and a cap mounted upon said end of said 50 core, thus extending beyond the bounds of said body portion.

4. An insulator-pin, comprising a body portion of insulating material provided with means for engaging an insulator, a metallic core 55 partially embedded within said body portion, said metallic core having one of its ends extended beyond the bounds of said body portion, a locking device for locking said core to a support, and separate means mounted directly upon the end thus extended for the purpose of insulating said locking device and the end of said metallic core from currents flowing adjacent to said insulator.

5. An insulator-pin, comprising a metallic 60 supporting member, a jacket of insulating ma-

terial enveloping said metallic member and provided with a surface for supporting an insulator, said jacket being provided with a plurality of hoods superposed one on the other, and means for mounting said metallic member upon a support.

6. An insulator-pin, comprising a metallic member, and a jacket of insulating material enveloping said metallic member and molded rigidly thereupon, said jacket of insulating 75 material being provided with a plurality of superposed hoods integral therewith, and further provided with a surface for engaging an insulator.

7. An insulator-pin, comprising a metallic 80 member provided with anchorages, and a jacket of insulating material enveloping said metallic member and engaging said anchorages, said jacket of insulating material being further provided with a plurality of super- 85 posed hoods and with a portion for supporting an insulator.

8. An insulator-pin, comprising a metallic member, means for supporting the same, and a member of insulating material mounted upon 90 said metallic member, said member of insulating material being provided with a hood integral therewith, and further provided with a threaded surface for supporting an insulator.

9. As an article of manufacture, a metallic 95 supporting member provided with a shank portion, and a jacket of insulating material provided with a plurality of superposed hoods and enveloping said metallic member but leaving said shank portion exposed.

10. An insulator-pin, comprising a body portion of insulating material provided with a threaded portion for detachably supporting an insulator, and also provided with a plurality of superposed hoods, said hoods terminating 105 at their bottoms in surfaces of different shapes, and means for supporting said body portion.

11. An insulator-pin, comprising a body portion of insulating material provided with means whereby it may be mounted upon a support, said body portion being provided with a surface for detachably engaging an insulator, and further provided with a plurality of hoods so as to virtually present an interrupt- 110 ed surface.

12. An insulator-pin, comprising a body portion of insulating material provided with means whereby it may be supported and with a surface for detachably engaging an insulator, said body portion being further provided with 115 a plurality of hoods integral therewith, and presenting a surface which is virtually interrupted.

13. An insulator-pin, comprising a plurality of separate hoods superposed one over the 120 other, the bottoms of the hoods being provided with drip-surfaces of different shapes, and a metallic member for supporting said separate hoods.

14. An insulator-pin, comprising a body 130

portion of insulating material provided with a plurality of hoods integral therewith, said hoods being provided with drip-surfaces of different conformity and virtually presenting 5 an interrupted surface, said body portion of insulating material being provided with means for supporting an insulator.

15. An insulator-pin, comprising a body portion of insulating material provided with 10 a hood and with a portion for engaging an insulator, said body portion being further provided with means whereby it may be mounted.

16. An insulator-pin, comprising a body portion and a plurality of separate hoods connected to the same, said body portion being further provided with means for engaging an insulator and with means whereby said body portion may be mounted. 15

17. An insulator-pin, comprising a body portion provided with hoods, a metallic member 20 provided with two ends, one of which is completely embedded within said portion so as to leave no part of said end exposed, the other end protruding from said body portion and provided with means whereby a fastening member may be connected therewith for the purpose of securing said body portion 25 firmly upon a cross-arm.

In testimony whereof I have signed my name to this specification in the presence of two sub- 30 scribing witnesses.

LOUIS STEINBERGER.
